UNITED STATES PATENT OFFICE.

ELMER E. F. CREIGHTON, OF SCHENECTADY, NEW YORK, ASSIGNOR TO GENERAL ELECTRIC COMPANY, A CORPORATION OF NEW YORK.

LIGHTNING-ARRESTER.

1,071,710.

Specification of Letters Patent.

Patented Sept. 2, 1913.

Application filed December 22, 1906. Serial No. 349,027.

To all whom it may concern:

Be it known that I, ELMER E. F. CREIGHTON, a citizen of the United States, residing at Schenectady, county of Schenectady, 5 State of New York, have invented certain new and useful Improvements in Lightning-Arresters, of which the following is a specification.

My present invention relates to protective 10 devices applicable to electrical conductors and apparatus, as a means for carrying off abnormal potential charges arising from any cause, such as atmospheric disturbance, static, resonance, line surges, etc.

15 The improved arrester hereinafter described is of the so-called multi-gap type, and is well adapted for use with electrical systems operating at potentials of several thousand volts.

20 Multi-gap arresters, as now commonly employed, comprise a plurality of conducting members, usually cylindrical, spaced apart to form a series of short air-gaps. The aggregate length of these air-gaps for

25 any given potential is considerably greater than could be employed if a single gap were used, and the electrostatic capacity of the conductors or cylinders is relied on, in a measure, to assist in breaking down the 30 gaps and initiate a flow of current when an abnormal potential arises on the line. When this break-down occurs there seems to be a progressive break-down of all the gaps beginning on the line side of the series and 35 traveling across to the other terminal. The time interval of this progression of the discharge is, of course, small, but it is nevertheless appreciable.

According to my present invention 40 arresters of the type above described are provided with adjuncts for assisting the establishment of initial current across the gaps, thereby rendering the series of gaps more certain in operation. The adjuncts above 45 mentioned are particularly sensitive to high frequency effects, so that the protective device as a whole becomes, in a sense, a selective device, and while readily transmitting energy of high frequency is relatively 50 inactive to low frequency, say of the mag-

nitude commonly used in electrical transmission.

The auxiliary means for influencing the break down of the multi-gaps comprises means for establishing an electrostatic field 55 across the various units or groups of which the arrester is composed so that each cylinder or conductor of each group acts as a condenser, and discharges or tends to discharge the high frequency oscillation to the 60 cylinder immediately adjacent. This electrostatic strain between various cylinders may be set up by arranging conductors or antennæ on opposite sides of the arrester units, one of the antennæ being connected 65 directly to the line conductor and the other antenna being connected to ground either directly or through other conductors or gaps.

The details of my invention will be better understood by reference to the drawing accompanying and forming a part of this specification.

Figure 1 is a diagrammatic representation of multi-gap arresters equipped with 70 antennæ and arranged for a three-wire system; Fig. 2 indicates diagrammatically the use of condensers between the antennæ and their respective conductors.

In Fig. 1 the line conductors 1, 2 and 3 80 are connected respectively to a neutral point, represented by a conductive bar 4, through multi-gap arresters 5, 6 and 7. Each of these arresters or groups comprises a plurality of units 8, and each unit may consist 85 of a plurality of metal cylinders spaced apart to form air-gaps and arranged in V-shape on a porcelain base. According to common practice, some of the V-shaped units may be shunted by a non-inductive 90 resistance 9 of ordinary type. The neutral point or bar 4 may be connected to ground through an auxiliary group 10, as this arrangement insures about the same number of gaps between line and line as between 95 any line and ground. On opposite sides of the V-shaped units of group 5, I arrange the antennæ 11 and 12 to establish an electrostatic field or stress across the intervening space. Similar antennæ 13 and 14 are ar. 100

ranged adjacent to group 6, and group 7 is likewise equipped with antennæ 15 and 16. The corresponding antennæ 11, 13 and 15 of these groups are connected respectively 5 to the line conductors 1, 2 and 3, and the opposing antennæ 12, 14 and 16 are connected directly with the neutral bar 4. The latter carries a fourth antenna 17 adjacent to the grounded group 10, but separated 10 from earth by the space intervening between it and the opposite antenna 18 is directly connected to earth.

Although I do not desire to be limited by any theory of operation, I believe that the 15 beneficial action of the antennæ may be explained on the theory that there is an electrostatic stress between each line antenna and the opposing antenna, and the effect is to charge up each series of cylinders as condensers, the charge depending upon the potential between cylinders and the capacity 20 of the cylinders. The charging current equals the product of the potential difference, times the capacity, times the frequency, 25 times 2π . For low frequencies, the charging current is small, and in fact, can be entirely suppressed by adjusting the position of the antennæ so that no spark passes from cylinder to cylinder. With this same potential difference and high frequency the 30 charging current assumes a density sufficient to form into a spark, and each straight line of gaps is bridged by sparks which have their source of potential in the antennæ. 35 When the gaps are ionized, the high potential charge on the line finds a comparatively easy path to ground and quickly relieves the line of its abnormal potential charge. As the antennæ simultaneously 40 start the sparks in a number of parallel lines, the arresters embody both the non-arcing qualities of many gaps in series and also the quick action of substantially simultaneous break-down across gaps.

45 It will be understood by persons skilled in the art that the employment of the antennæ as above described permits a material addition to the number of gaps which may be employed on any given line potential, thereby increasing the certainty of rupturing the line current in case the line current follows through on the lightning discharge.

Fig. 2 illustrates the use of condensers 19 and 20 to separate their respective antennæ 21 and 22 for the purpose of diminishing the risk of a short-circuit between either of the antennæ and any of the conducting cylinders of the multi-gap units. These 60 condensers allow the high frequency oscillations to pass through without obstruction, and since the dielectric strength of the condenser can be made great, the antennæ can

be brought nearer the units without risking a short circuit.

65

Fig. 2 is intended to be only diagrammatic and to indicate that condensers may be applied to any or all of the antennæ shown in Fig. 1. Although the system shown in detail in Fig. 1 is arranged for a three-phase 70 system, it could obviously be changed to meet the requirements of other polyphase circuits, or even of a single-phase system.

What I claim as new, and desire to secure by Letters Patent of the United States, 75 is,—

1. In a protective device, the combination with a plurality of spark gaps forming a discharge path, of antennæ disposed on opposite sides of said path and adjacent thereto at intervals along the discharge path to influence the break-down potential of said path.

2. In a protective device, the combination with a plurality of conductors spaced apart to form air gaps, of a grounded antenna mounted closer to some of the groups than to the others, and a line antenna mounted closer to some of the other groups, whereby an electrostatic stress is established between said antennæ to influence the break-down potential of said device.

3. The combination with a plurality of multi-gap units disposed in series and connected to a line conductor, of antennæ on opposite sides of said units to influence the break-down potential across said gaps.

4. In a protective device, the combination with a plurality of conductors separated by air gaps and arranged to form a zig zag discharge path, of antennæ mounted close to the angles of said path on opposite sides thereof, and connections whereby an electrostatic stress is exerted between 105 said antennæ and thereby the breakdown potential of said path is influenced.

5. The combination with a multi-gap protective device for electrical conductors, of antennæ disposed to set up an electrostatic stress across said gaps, and condensers interposed between said antennæ and other conductors of the system.

6. In a protective device, the combination of series of conductors spaced apart to form 115 a series of air gaps, an antenna on each side of said series of gaps, and means for maintaining a sufficient difference of potential between said antennæ to influence the breakdown of said gaps by electrostatic influence.

7. In a protective device, the combination with a series of conductors spaced apart to form a zig zag line of air gaps, a grounded antenna on one side of said line 125 adjacent some of said gaps, and an antenna

on the other side adjacent other gaps, and means for maintaining between said antennæ a difference of potential for influencing the break-down voltage of said 5 gaps.

8. In a protective device, the combination with a series of conductors mounted to form a zig zag discharge path comprising a series of air gaps, and antennæ on opposite sides of said path, and means for main- 10

taining a difference of potential between said antennæ for exerting an electrostatic stress on some of said gaps to influence the breakdown voltage of said discharge path.

In witness whereof, I have hereunto set my hand this 21st day of December, 1906.

ELMER E. F. CREIGHTON.

Correction in Letters Patent No. 1,071,710.

Corrections in Letters Patent No. 1,071,710

It is hereby certified that in Letters Patent No. 1,071,710, granted September 2, 1913, upon the application of Elmer E. F. Creighton, of Schenectady, New York, for an improvement in "Lightning-Arresters," errors appear in the printed specification requiring correction as follows: Page 2, line 11, strike out the word "is"; same page line 46, second occurrence, strike out the article "the"; and that the said Letters Patent should be read with these corrections therein that the same may conform to the record of the case in the Patent Office.

Signed and sealed this 7th day of October, A. D., 1913.

[SEAL.]

R. T. FRAZIER,

Acting Commissioner of Patents.
